UNITED STATES PATENT OFFICE

FRANK J. SCHLEICHER, OF ST. LOUIS, MISSOURI

PAPER BOX

Application filed November 10, 1930. Serial No. 494,553.

My invention relates to boxes of cardboard or similar material and more particularly to such boxes formed in heart or other shapes wherein portions of the sides are curved.

Heretofore, each half of such boxes has comprised a side wall, a bottom fitted within the side wall and a base attached to the lower face of the bottom and projecting outwardly beyond the side wall. At first, the side wall was attached to the base by means of an edge strip secured to the side wall and then folded outwardly and downwardly around the exposed edge of the base. This was, necessarily, a manual operation and, therefore, the cost of manufacturing boxes formed in this manner was high. Later, as shown in reissue Letters Patent Nos. 17,183 and 17,328 issued to me on January 1, 1929, and June 18, 1929, respectively, there was made a box of this type which could be made on a machine because the side wall was attached to the bottom and then the base was attached to the bottom by means other than the attaching means for the side wall. However, no box has yet been devised which can be manufactured on a machine and in which the side wall is attached directly to the base.

Also, heretofore glue has been relied upon entirely in securing the various parts of the box to one another and when boxes are manufactured rapidly in large quantities trouble has been encountered in providing sufficient pressure upon the parts glued to make the glue stick to the extent necessary to form a strong box.

The objects of my invention are to provide a box of the class described in which the side wall is secured to the base and to provide a box in which the parts are secured to one another in such a way that glue is not wholly relied upon to maintain the parts in adjusted position.

A heart shaped box embodying my invention is shown in the accompanying drawing wherein similar characters are used to designate similar parts and, although, for the sake of convenience and clarity I have shown only half of a box it is to be understood that a complete box consists of two such halves arranged with the side walls thereof slidably

fitted one within the other: Fig. 1 is a plan view of the box part and Fig. 2 is a section along the lines 2—2 in Fig. 1.

Referring to the figures the embodiment of my invention shown therein comprises a base A and a side wall B. The base A has the edge thereof curved in a heart shape and the side wall B follows the contour of the base, as shown in Fig. 1. Projecting outwardly from and preferably at substantially right angles to the side wall B is a flange C which is preferably an integral part of the wall. The flange may be notched as at D to allow the side wall to be bent in the desired shape to follow the contour of the base. The side wall B is preferably formed of one strip and one end of the strip may have an overlapping part E arranged to extend over the other end whereby the ends of the side wall are secured together in the finished box. Preferably, the flange D terminates short of the overlapping part E.

The marginal portion F of the base A extends outwardly past the side wall B along and beyond the outer edge of the flange D and is reversed over the edge of the flange and crimped thereon as at G. Paper or cardboard of the weight commonly used can be crimped in the manner shown, but some cardboards cannot be stretched to the extent required in the crimping operations and, therefore, it may be necessary that the reversed part G of the base likewise be notched as at D' so that a firm contact may be had when it is crimped over the edge of the flange C.

Also, so that the box will be as strong as possible I prefer that any notches D' in the reversed part G of the base are positioned in respect to the notches D in the flange C so that the notches in the two parts will not register, but will lie between one another as shown in Fig. 1. In forming a heart shape box the notches D and D' at the point a and the recess b are necessarily somewhat larger than the notches provided on the circumference of the sides.

It should be noted that in the figures the notches D are closest together where the curvature of the side wall B is greatest and are spaced further apart where the side wall B

is more nearly straight. Likewise, if it is necessary to have the notches D' in the reversed part G these notches will also be closest together where the wall B is curved the most.

In forming a box as described herein a small amount of glue may be included between the contacting surfaces of the flange C and the marginal portion F of the base A and the reversed part G, but it may readily be seen that if the parts are formed as described above the crimping of the marginal portion of the base over the flange will hold the parts of the box in predetermined fixed relation and a rugged structure will be obtained.

While I have shown a heart shaped box in the drawing and described such a box above it may be understood that boxes embodying my invention may be made in various sizes and shapes without deviating from the spirit of my invention as included in the claims set forth below.

What I claim as new and desire to secure by Letters Patent, is:—

1. A cardboard box comprising a side wall and a base, said side wall having an outwardly projecting flange and said base having the marginal portion thereof extending along and outwardly beyond said flange and means for securing said flange to said marginal portion of said base.
2. A cardboard box comprising a side wall and a base, said side wall having a flange projecting outwardly therefrom at substantially right angles thereto and said base having the marginal portion thereof reversed and crimped over said flange whereby said side wall is secured to said base.
3. A cardboard box comprising a side wall and a base having a curved edge, said side wall having an outwardly projecting flange notched to allow said wall to follow the contour of said base and the marginal portion of said base being reversed and crimped over said flange whereby said side wall is secured to said base.
4. A cardboard box comprising a side wall and a base having a curved edge, said side wall having an outwardly projecting flange notched to allow said wall to follow the contour of said base, the marginal portion of said base being reversed and crimped over said flange whereby said side wall is secured to said base, and said reversed portion of said base being likewise notched to allow a firm contact thereof with said flange.
5. A cardboard box comprising a side wall and a base having a curved edge, said side wall having an outwardly projecting flange notched to allow said wall to follow the contour of said base, the marginal portion of said base being reversed and crimped over said flange whereby said side wall is secured to said base, said reversed portion

of said base being likewise notched to allow a firm contact thereof with said flange and the notches in said flange being positioned relative to the notches in said reversed portion so as not to register therewith.

In witness whereof I have signed my name to the foregoing specification.

FRANK J. SCHLEICHER.
